UNITED STATES PATENT OFFICE.

ERNEST G. JOHNSON, OF WAVERLEY, MASSACHUSETTS, ASSIGNOR, BY MESNE ASSIGNMENTS, TO WESTINGHOUSE ELECTRIC & MANUFACTURING COMPANY, A CORPORATION OF PENNSYLVANIA.

LOW-VOLTAGE CIRCUIT BREAKER.

Application filed December 10, 1918. Serial No. 266,151.

To all whom it may concern:

Be it known that I, ERNEST G. JOHNSON, a citizen of the United States, residing at Waverley, in the county of Middlesex and 5 State of Massachusetts, have invented new and useful Improvements in Low-Voltage Circuit Breakers, of which the following is a specification.

This invention has for its object to provide a remote control switch and circuit breaker, which is operative to break an alternating current circuit upon decrease in potential or failure of the alternating current.

On the accompanying drawing,—

Figure 1 illustrates in front elevation a circuit breaker embodying the invention.

Figure 2 represents a vertical section through the same.

Figure 3 illustrates in detail the latch mechanism which constitutes a novel feature of the circuit breaker.

Figure 4 is a diagrammatic view, showing certain of the operative elements and the circuits on which they are located.

In many of its constructional details, the circuit breaker, which I have illustrated upon the drawings as embodying the present invention, is like the apparatus illustrated and described in Letters Patent No. 1,179,957, 25 to Granville E. Palmer, dated April 18, 1916, and reference may consequently be had thereto for a more detailed explanation of certain 30 of the parts or elements to which I shall but briefly refer in the following specification.

The main switch for the circuit, which in figure 4 comprises the two lines 10 and 11, 35 includes the stationary contacts 12, 13, and the cooperating movable laminated brush contact members 16, 17. The faces 14 and 40 15 of the stationary contacts 12 and 13 are arranged at an angle of approximately 45°, the members 16 and 17 likewise forming a right angle, so as to make proper contact with said faces. The brush contacts are secured to but are insulated from a cross bar 45 18, secured to an arm or lever 20 movable about a pivot or shaft 19. The movable switch members are moved into and out of contacting relation with the stationary members as the arm 20 is swung about its axis. The lever 20 is moved to closed position by a main solenoid magnet 24, the armature or plunger 25 of which is pivoted to the arm 20 by a pin 26. The lever is opened by one

or more springs 22 coiled about the shaft 19 55 and engaged with the arm or lever. The solenoid 24 is placed in a branch circuit, for which current is derived from the main circuit 10, 11. This branch circuit comprises the conductors *a*, *b*, *c* and *d*, as shown by 60 the diagram in Figure 4. This branch circuit is closed by one instrumentality and automatically opened by another, as will be explained. For closing the branch circuit to the solenoids 24, a solenoid magnet, comprising two solenoid coils 27, 27, is placed in a second branch circuit, the conductors of which are indicated at *e* and *f*, this magnet being in multiple with the magnet 24. This branch circuit may extend to a remote point, 65 and have a switch *h* included therein to provide a remote control for the main switch. The magnet, comprising the coils 27, forms the subject-matter of an application of 70 Granville E. Palmer, Serial No. 266,132, filed December 10, 1918, *per se* and constitutes no separate feature of the present invention, so that any equivalent for it may 75 be utilized. It is particularly adapted for use in the present circuit breaker because of 80 certain characteristics which will be briefly referred to. For cooperation with the solenoids 27, there are two U-shaped members 28, 29, arranged in opposition, and constituting together an armature, in which there is a 85 complete magnetic circuit when an alternating current of predetermined potential is passed through the solenoid coils. Each of said members 28 and 29 has arms or plungers extending into the solenoid coils, and 90 which are brought into contact to form a complete magnetic circuit or field when the solenoid coils are excited by a current of desired potential. When such current is passing through the solenoids, the two-part armature floats and produces no hum or chatter. The cross bar of the armature member 28 is provided with a lateral projection 30, upon 95 which a movable contact member 31 (properly insulated therefrom) is mounted so as to make contact with and complete the circuit through two stationary spring contact members 32, 32, arranged in the branch circuit in which the main solenoid 24 is located. Assuming that the said branch circuit is otherwise closed, it will be understood that, when the solenoids 27 are energized to cause the contact member 31 to be 100 105

moved to active position, the main solenoid 24 is energized to move the arm 20 from open to closed position, as shown in Figure 3, thereby moving the main switch members 16 and 17 to close the main circuit through the stationary contacts 12 and 13. From the stationary contact members 13 the working circuit is indicated at 9.

In order to break the branch circuit through the solenoid 24 as soon as it has performed its function, a supplemental or contactor switch is employed, which is substantially like that described in the Palmer patent hereinbefore referred to. This mechanism comprises a member or contactor 33, adapted to be brought into electrical contact with the two stationary members 34, 34, which are respectively connected to the conductors *c* and *d* in the shunt or branch circuit. The movable member 33 is operated by an arm pivoted upon the shaft 19. This arm, which is indicated at 35, is provided with a pivoted extension 36, hung thereto by a pin 37. A coiled spring 38 is interposed between the extension and the arm, so as to permit one to yield relatively to the other and to permit a certain flexibility of play of the contactor 33. A coiled spring 39, between the lever 35 and a shoulder on the arm 20, tends to throw the arm 35 and the contactor 33 downwardly, so that the latter will rest upon the stops 40. The arm 20, which is bifurcated at its lower pivoted end, is provided with a bridge or cross bar 41, one edge of which is adapted to engage the lever 35, as the arm 20 moves from its closed position in Figure 3 to its open position in Figure 2, and to swing said lever about its pivot, so as to bring the contactor or member 33 in circuit-closing position in engagement with the contacts 34. When the said lever has reached this position, it may be there held by a hooked latch 42. This latch is spring-tensioned by a coil spring 43 normally to swing to the right, in Figures 2 and 3, so as to engage a finger 44 projecting from the pivoted end of the lever 35. The hub of the latch 42 is pivoted upon a cross shaft 45. The latch is so located in reference to the arm 20 that, as the latter reaches its closed position, the cross bar 41 thereon will exert a camming action on the latch 42 to swing it outwardly and cause it to release the lever 35, upon which, of course, the spring 39 will force the lever downwardly. The described construction and arrangement of parts are for the purpose of ensuring that the contactor 33 is, when the main switch is open, in electrical contact with the contact members 34 of the branch circuit 24, and there remains until the lever 20 has almost reached its closed position. As the arm 20 and the main switch members approach their closed positions, the latch 42 is moved to release the lever 35, which

promptly, under the influence of the spring 39, swings the contactor 33 away from the contacts 34 and breaks the branch circuit.

As I have previously stated, the main switch members and the arm 20 are moved to closed position by the solenoid 24, acting upon the plunger 25, and I have also explained that, as soon as they approximately reach this position, the branch circuit through said solenoid is broken. To hold the main switch members in their closed position, I employ a novel lock, which is automatically operated by the solenoid 24 or its equivalent to lock the lever 20 in closed position, and which is automatically released when the circuit through the solenoids 27 fails or reaches a predetermined low voltage. This locking mechanism comprises a bell-crank lever, indicated as a whole at 46, and having arms 47 and 48, as shown in Figures 2 and 3. The arm 48 is formed of soft iron (laminated, if desired), so as to constitute a second armature for the solenoid magnet 24. It extends downwardly across the end of the coil and plays in a slot 49 in the plunger 25. The arm 47 projects across the upper end of the arm 20, and it is bifurcated or yoke-shaped, between the arms of which there is a pin 50 and a roller 51. In the end of the arm 20 there is a spring-pressed beveled dog 52, which, when the arm 20 is in its closed position, is adapted to engage the roll 51 on the arm 47, and thus hold the arm 20 and the main switch members in closed position. The bell-crank lever 46 is fulcrumed upon a pivot 53, which is so located that, when the arm 47 is in the position shown in Figure 3, the thrust of the dog 52 against the roll 51 on the arm 47 is resisted positively, and the arm 20 is held in its locked position. When the main switch is open and the arm 20 is in the position shown in Figure 2, the arm 47 is so located that the dog 52 could move thereunder without touching it, should the arm 20 be swung to the right. When the circuit through the solenoid 24 is closed, both the plunger 25 and the armature 48 are moved, and the arm 47 is swung down to its locking position into the path of movement of the dog, so as to engage the dog 52 after the latter has passed it and lock the arm 20 and the main switch members in their closed position. It will thus be seen that I have provided a mechanical lock for the main switch, which, by its mechanical action, holds the main switch closed, but which is magnetically moved from its inactive or inoperative position to its active or operative locking position just prior to the closing of the main switch. The lock is released upon failure of current through the solenoids 27, or when the potential has dropped below a certain voltage. To this end, the bell-crank 46 has an arm or tail 54, which projects to the right

in Figure 3, and which is adapted to be engaged by a member 55 depending from the armature 28 of the solenoids 27. This member 55 is shown as in the form of a screw, so that it may be adjusted longitudinally, and it is screwed into the projection 30. The parts are so located that, when the armature 28 is released by the solenoids 27, the member 55, in dropping, will strike the arm 54 10 a hammer blow and lift the locking arm 47 so as to release the dog 52 and permit the arm 20 to be moved to its open position, thereby opening the main switch members.

It will of course be understood that the various parts are properly insulated from each other, where insulation may be needed, and that they are all suitably mounted upon a back-board of suitable material. The various conductors of the main, working and branch circuits are brought to proper terminals where they may be easily connected, as described.

In operation, assuming that an alternating current of predetermined potential is supplied from a suitable source to the main circuit and that the main switch is closed to the working circuit *g*, current is supplied by the branch circuit *f* to the solenoids 27. The two-part armature thereof is in its operative position with the armature 28, 29 floating in the magnetic field and holding the member 55 in a raised position. At this time, the lock 47 is locking the arm 20 and the main switch movable members in their closed positions; and the contactor member 33 is in the position shown in Figure 3, so that no current is passing through the main solenoid 24. Assuming that the current gradually drops in potential, the following results occur. Due to loss in energy, the armature 28, 29, moves downwardly until the member 29 rests upon the top of the coils 27, where the parts remain during the further decrease in potential, until such loss in energy occurs that the weight of the member 28 causes it to be released. The member 28 has been held against movement during this gradual decrease in potential because the two members 28 and 29 constitute magnets, which remain in contact by their mutual magnetic attraction. As soon as the magnetic force decreases, as stated, so that the weight of the member 28 causes it to be released, it suddenly drops, and, by reason of its acquired momentum, the screw 55 strikes the arm 54 with a hammer blow, thereby lifting the lock 47, whereupon the arm 20 and the movable members of the main switch are immediately swung to open position. As the arm 20 moves to open position, it moves the supplemental switch member 33 to closed position, as previously explained, and the latch 42 holds it in such closed position. Consequently, upon restoration of current of proper potential in the main circuit and in

the branch circuit which includes the solenoids 27, the armature 28 is raised to bring the switch member 31 into contact with the contacts 32, so as to close the branch circuit of the main solenoid 24, thereby causing the main switch to be closed, as previously described.

The main switch is electro-magnetically closed and is self-opening. The electro-magnet which operates the main switch is in a normally open circuit containing two supplemental switches, one of which is controlled by said electro-magnet, and the other of which is controlled by an electro-magnet in a normally closed branch circuit at all times in closed connection with the main circuit. The main switch is locked mechanically in closed position by a mechanical lock, which, however, is electro-magnetically actuated by the same electro-magnet which closes the main switch, and which is tripped by the armature of the magnet located in the normally closed branch circuit.

In the embodiment of the invention herein illustrated and described, I have accomplished several important results by novel mechanism. The main switch is held in its closed position mechanically, without the use of springs, this being achieved by the lock 47 which is engaged by the dog 52. To release the main switch and afford it an opportunity for self-opening, the lock is swung about its pivot so as to disengage it from the dog. The lock itself is held rigidly in locking position by the armature 48 and electro-magnet 24, only during the closing movement of the main switch, since it is only during this movement that the electro-magnet is energized. As soon as this movement ceases, the current in magnet 24 is cut off by the auxiliary circuit breaker 33, 34, 34. The breaking of the circuit through the magnet 24 does not have any effect on the lock, which continues mechanically to hold the main switch closed until such time as the magnet 27, due to current failure to a predetermined point, permits the armature 28 to drop, and, with a hammer blow, to strike the tail 54 of the lock and move the locking end thereof out of the path of the dog 52. The lock does not move or yield, when the main switch is again being moved to closed position, since, as stated, it is then being held or located rigidly against movement, and hence the dog 52 is yieldingly mounted so that, in the final closing movement of the main switch, the dog yields or is pressed downwardly so as to ride under the rigidly held lock. Hence of the two elements, i. e. the dog on the switch and the lock, one is moved or yields to permit the switch to be completely closed, and the other is moved to permit the switch to open without the necessity of the opening means (the armature 28) overcoming the yielding means or

spring which is essential to permit the switch-closing operation. The power required to close the switch may be relatively great according to the size and weight of the moving parts, whereas the power necessary to permit the switch to open should be as small as possible, in order that the magnet 27, which is constantly in circuit, should consume the least amount of current. Thus, in releasing the switch, the mechanism is so constructed as to obviate the compression or flexure of the spring which yields when the switch is being closed, and to provide for the movement of the lock to release the spring-tensioned dog. The time element is important, since the dog and the lock must interlock instantly on the closing movement of the switch in order to prevent any rebound of the switch and the movement of the dog in the opposite or switch-opening direction. To secure this result, the dog is moved endwise or longitudinally by the direct thrust of its spring, and, after the end of the dog rides under the roller 51 on the lock and yields in so doing, it is instantly forced endwise by its spring behind the roller as soon as it passes under the axis of the roller. In fact, the roller is rotated on its axis by the dog as the latter rides thereunder. The flat face of the dog lies against the roller and its end projects perpendicularly only slightly beyond a line connecting the axes of the roller 51 and the pivot 53, when the lock is mechanically holding the switch closed, and hence, as only a relatively very light blow of the armature 28 against the tail 54 of the lock is thus required to effect the release of the dog, the armature may be light in weight and the magnet correspondingly small so as to consume a minimum amount of current.

Having thus explained the nature of my said invention, and described a way of making and using the same, although without attempting to set forth all of the forms in which it may be made or all of the modes of its use, what I claim is:—

1. A low voltage circuit breaker comprising a self-opening main switch, a closing mechanism for the main switch including an electro-magnet, a mechanical lock for holding said main switch closed, and operated to closed position by said electro-magnet, and means responsive to voltage variations in the line arranged to trip said lock mechanically and permit said main switch to open on failure of line potential.

2. A low voltage circuit breaker for use with a main circuit deriving its current from a suitable source of potential, comprising a self-opening main switch, a normally open branch circuit including an electro-magnet for closing the main switch, and a mechanical lock for said main switch supported independently thereof and associated with and

operatively moved to locked position by said main-switch-closing electro-magnet but held mechanically in locked position.

3. A switch mechanism comprising a self-opening switch, including a movable member, a lock for mechanically locking said member in closed position, an electro-magnet, an armature therefor operatively connected to said movable member, and a second armature therefor operatively connected to said lock.

4. A low voltage circuit breaker comprising a self-opening switch having a pivoted arm, a pivoted locking member supported independently of said arm for mechanically engaging and locking said arm in closed position, and electro-magnetic mechanism common to said arm and said member for actuating said arm and said member independently of each other.

5. A low voltage circuit breaker comprising a self-opening switch having an arm pivoted at one end, a movable locking member supported independently of said arm arranged to engage the free end of said arm and lock it in closed position, and a solenoid having a plunger connected to said arm and an armature connected to said locking member.

6. A switch mechanism comprising a self-opening switch including an arm pivoted at one end, and having a dog at its free end, a pivoted locking lever supported independently of said arm arranged to engage said dog and mechanically lock said arm in closed position, and electro-magnetic mechanism arranged to move said arm and said lever to interlocked position.

7. A switch mechanism comprising a self-opening switch including an arm pivoted at one end, and having a dog at its free end, a pivoted locking lever arranged to engage said dog and mechanically lock said arm in closed position, and electro-magnetic mechanism arranged to move said arm and said lever to interlocked position, in combination with normally energized electro-magnetic mechanism arranged to trip said lock responsive to failure of current.

8. A low voltage circuit breaker comprising a main switch; an electro-magnetic mechanism for closing said switch and conditioned for operation by closing a branch circuit deriving current from the main circuit; a movable lock for mechanically locking the main switch in closed position, and operated independently of the switch by the electro-magnet of said electro-magnet mechanism; and electro-magnetic mechanism in a normally closed branch circuit deriving potential from said main circuit, for tripping said lock in response to voltage failure.

9. A low voltage circuit breaker comprising a self-opening main switch; an electro-

- 5 magnetic mechanism for closing the switch including a solenoid and a plunger operatively connected to said switch; a mechanical lock arranged to mechanically lock said main switch in closed position and having an operating member constituting an armature of said solenoid; and normally energized electro-magnetic mechanism responsive to variations in voltage on the main switch, for tripping said lock, conditioned for tripping operation by failure of line voltage on the closed main switch.
- 10 10. A low voltage circuit breaker comprising a self-opening main switch; an electro-magnetic mechanism for closing the switch including a solenoid and a plunger operatively connected to said switch; a movable lock arranged to mechanically lock said main switch in closed position and having an operating member constituting an armature of said solenoid; a gravity-operated member for tripping said lock, an armature connected to said member normally to hold it in raised inactive position, and an electro-magnet associated with said armature and normally deriving current from the main circuit.
- 15 11. A low voltage circuit breaker comprising a self-opening main switch, an electro-magnetic mechanism for closing the switch including a solenoid and a plunger operatively connected to said switch; a movable lock arranged to mechanically lock said main switch in closed position and having an operating member constituting an armature of said solenoid; electro-magnetic mechanism having means rendered operative by failure of current in the magnet, for tripping said lock; and supplemental switches for controlling the operation of the first-mentioned main-switch-operating electro-magnetic mechanism, one switch being operated by said mechanism and the other by the second-mentioned electro-magnetic mechanism.
- 20 12. A circuit breaker comprising a stationary contact, an electromagnetically-closed self-opening movable contact, and a mechanical lock for holding the movable contact in closed position, said lock including an element movable with the movable contact and a complementary member mounted on a stationary part of the circuit breaker, one of said elements being relatively inoperative to permit the members to interlock on the closing movement of said movable contact and the other member being movable to permit the disengagement of said members.
- 25 13. A circuit breaker comprising fixed and movable contacts adapted to complete and rupture an electric circuit, a support for the fixed contact, a movable support for the movable contact, and complementary interlocking members for mechanically holding the movable support in circuit closed position, one of said members being yielding relatively to the other to permit closing movement of the movable support and the other said member being movable to release the first said member and permit said movable support to move to circuit-open position.
- 30 14. A circuit breaker comprising fixed and movable contacts adapted to complete and rupture an electric circuit, a support for the fixed contact, a movable support for the movable contact, complementary interlocking members for mechanically holding the movable support in circuit closed position, and means by which one of said members is positioned or held rigidly against movement only during the closing movement of the movable support.
- 35 15. A circuit breaker comprising fixed and movable contacts adapted to complete and rupture an electric circuit, a support for the fixed contact, a movable support for the movable contact, complementary interlocking members for mechanically holding the movable support in circuit closed position, means by which one of said members is positioned or held rigidly against movement only during the closing movement of the movable support, and means for tripping said member to release the other member and permit opening movement of said movable support.
- 40 16. A circuit breaker comprising fixed and movable contacts adapted to complete and rupture an electric circuit, a support for the fixed contact, a movable support for the movable contact, electromagnetic means for moving said movable support to closed position, complementary interlocking members for mechanically locking said movable support in closed position, means by which one of said members moves or yields only to permit opening movement of the movable support and is held rigidly against movement during the closing of said movable support, and means responsive to voltage variation for tripping said member to permit opening movement of said movable support.
- 45 17. A circuit breaker comprising fixed and movable contacts adapted to complete and rupture an electric circuit, a support for the fixed contact, a movable support for the movable contact, electromagnetic means for moving said movable support to closed position, complementary interlocking members for mechanically locking said movable support in closed position, means by which one of said members moves or yields only to permit opening movement of the movable support and is held rigidly against movement during the closing of said movable support, means responsive to voltage variation for tripping said member to permit opening movement of said movable support.

movement of said movable support, and means by which the other interlocking member yields or moves during closing movement of the movable contact to permit the 5 interengagement of said interlocking members.

18. A switch mechanism comprising fixed and movable contacts adapted to complete and rupture an electric circuit, a movable support for the movable contact, a movable lock for mechanically holding said support in closed position, and means for rigidly positioning said lock only during the closing movement of said movable support.

19. A switch mechanism comprising fixed and movable contacts adapted to rupture or complete an electric circuit, a stationary support for the fixed contact, a movable support for the movable contact, interlocking members mounted on said supports respectively for holding the contacts in closed position, one of said members being movable relatively to the other to permit their engagement and said other member being movable only to permit their disengagement, and means responsive to voltage variations in said circuit for tripping said last-mentioned member.

20. A switch mechanism comprising fixed and movable contacts adapted to rupture or complete an electric circuit, a stationary support for the fixed contact, a movable support for the movable contact, interlocking members mounted on said supports respectively for holding the contacts in closed position, one of said members being movable relatively to the other to permit their engagement and said other member being movable only to permit their disengagement, 40 means responsive to voltage variations in said circuit for tripping said last-mentioned member, and means by which said last-mentioned member is held against movement during only the closing movement of said movable support.

21. A switch mechanism comprising a fixed contact, a movable contact mounted to move in the arc of a circle between contact-closed and contact-open positions for completing or rupturing an electric circuit, means for causing such movement, a lock to mechanically lock said movable contact in switch-closed position and an electromagnetic device responsive to voltage variations in said circuit for controlling the said means when energized and for tripping said lock when deenergized.

22. A switch mechanism comprising a stationary support, a fixed contact thereon, a movable arm, a movable contact thereon, said contacts being adapted to rupture or complete a working circuit, an electromagnet for moving said arm from open to closed position, interlocking members, one supported by said stationary support and the

other supported by and movable with said arm for mechanically holding said arm in closed position, one of said members being yielding relatively to the other to permit their engagement, and said other member being movable to permit their disengagement, and an electromagnetic device for closing a circuit through the first-mentioned electromagnet when energized, and for tripping said last-mentioned interlocking member when deenergized.

23. A switch mechanism comprising a stationary support having a stationary contact, a movable arm having a movable contact, a lock movably mounted on said stationary support, a yielding dog carried by said arm adapted to engage said lock and to yield relatively thereto during closing movement of said arm, means for holding said lock against movement during said closing movement of said arm, and an electromagnetically controlled device for tripping said lock relatively to said dog to permit opening movement of said arm.

24. A circuit breaker comprising a switch, means urging said switch to open position, complementary interlocking members for holding said switch closed, means acting only during the closing movement of said switch for urging one of said members to locking position, and means for moving said member out of locking position to cause the switch to open.

25. A circuit breaker comprising a switch, means urging said switch to open position, complementary interlocking members for holding said switch closed, electromagnetic means acting only during the closing movement of said switch for urging one of said members to locking position, and means for moving said member out of locking position to cause the switch to open.

26. A circuit breaker comprising a switch, means urging said switch to open position, complementary interlocking members for holding said switch closed, means acting only during the closing movement of said switch for urging one of said members to locking position, and means acting on loss of line potential for moving said member out of locking position.

27. A circuit breaker comprising a switch, means urging said switch to open position, complementary interlocking members for holding said switch closed, means acting only during the closing movement of said switch for urging one of said members to locking position, and an electromagnet subjected to line voltage effective on its de-energization to move said member out of locking position.

28. A circuit breaker comprising a switch, means urging said switch to open position, complementary interlocking members for holding said switch closed, means acting

only during the closing movement of said switch for urging one of said members to locking position, means for moving said member out of locking position, and an electromagnetic for holding said moving means inoperative.

29. A circuit breaker comprising a switch, means urging said switch to open position, complemental interlocking members for holding said switch closed, means acting only during the closing movement of said switch for urging one of said members to locking position, means for moving said member out of locking position, and an electromagnetic subjected to line potential energizable to hold said means inoperative.

30. A circuit breaker comprising a switch, means urging said switch to open position, complemental interlocking members for holding said switch in closed position, electromagnetic means for closing said switch and moving one of said members into locking position, means acting to de-energize said electromagnetic means when said switch closes, and means for moving said member out of said locking position to cause said switch to open.

31. A circuit breaker comprising a switch,

means urging said switch to open position, complemental interlocking members for holding said switch in closed position, electromagnetic means for closing said switch and moving one of said members into locking position, means acting to de-energize said electromagnetic means when said switch closes, and means acting on failure of line potential to move said member out of locking position to cause said switch to open.

32. A circuit breaker comprising a switch, means urging said switch to open position, complemental interlocking members, one of said members comprising a lever, for holding said switch in closed position, electromagnetic means for closing said switch and for moving said lever to locking position, means acting to de-energize said electromagnetic means when said switch closes, a solenoid subjected to line potential, and an armature for said solenoid acting on de-energization of said solenoid to impinge on said lever and move it out of locking position to cause said switch to open.

In testimony whereof I have affixed my signature.

ERNEST G. JOHNSON.
